UNITED STATES PATENT OFFICE.

LOUIS ALEXANDRE CADORET, OF PAWTUCKET, RHODE ISLAND.

UNIVERSAL METAL BOBBIN.

Application filed May 19, 1924. Serial No. 714,457.

To all whom it may concern:

Be it known that I, LOUIS A. CADORET, a citizen of the United States, residing at Pawtucket, in the county of Providence and State of Rhode Island, have invented certain new and useful Improvements in Universal Metal Bobbins; and I do declare the following to be a full, clear, and exact description of the invention, such as will 10 enable others skilled in the art to which it appertains to make and use the same.

My invention relates to improvements in bobbins for use in the shuttles of looms, and I prefer to term such bobbin a universal metal bobbin, as it is preferably constructed from sheet metal and may be universally used in all sorts of shuttles.

One object of the invention is to provide a bobbin which is much smaller than the usual bobbins, due to its thin sheet metal construction, which is of great advantage, as it permits a greater amount of thread to be carried and thus saves a great deal of time in the operation of looms, by cutting down the changing of bobbins to the minimum.

A further object is to provide a bobbin of the type set forth in which means for engagement with an ordinary bobbin holder of a shuttle, and means for preventing slipping of the thread on the bobbin, are provided merely by stamping the material from which such bobbin is constructed.

A still further aim is to provide a bobbin formed of two sections and to secure a driving washer in place by and between said sections, said washer coming into play when the bobbin is being rotated during the thread winding operation.

With the foregoing and minor objects in view, the invention resides in the novel subject matter hereinafter described and claimed, the description being supplemented by the accompanying drawing.

Figure 1 is a side elevation.

Figure 2 is a vertical longitudinal sectional view.

Figure 3 is an enlarged longitudinal section showing more particularly the means for centering the bobbin on the spindle.

Figure 4 is a vertical transverse sectional view as indicated by line 4—4 of Fig. 2.

Figures 5, 6 and 7 are fragmentary elevations showing different provisions which

may be made to permit the bobbin to be held by different forms of bobbin holders.

In the drawing above briefly described, the numeral 1 designates a thin sheet metal tube which forms the shank of the bobbin, said tube being preferably formed by rolling a piece of sheet metal upon itself and connecting its edges by dove-tail tongues 2 on one edge, received in dove-tail notches 3 formed in the other edge (see Fig. 1). At intervals, the tube 1 is preferably stamped outwardly to provide it with spaced circumferential ribs 4 which prevent slippage of thread thereon, and one end portion 5 of said tube is preferably enlarged somewhat to a diameter equal to or slightly greater than the diameter of the tube, taken in a plane with one of the ribs 4. This enlarged end of the tube is bent outwardly to provide a transverse flange 6 which is preferably continuous throughout the circumference of the tube.

In order to center the tube 1 upon either a driving spindle or the spindle within a shuttle, circumferentially spaced portions of said tube are stamped inwardly to provide spindle-engaging projections which are preferably in the form of longitudinally disposed resilient tongues 7.

Contacting with the outer side of the flange 6, I have shown a driving washer 8 which is instrumental in engaging a driven spindle to rotate the bobbin when thread is being wound upon it. A hollow, stamped metal head 9 which preferably tapers inwardly, surrounds the enlarged end portion 5 of the tube 1 and extends around the flange 6 and washer 8, the outer end of this head being bent inwardly as indicated at 10, to contact with the outer side of said washer and securely confine it against the flange 6. In Figs. 1 and 2, the head 9 is inwardly stamped as indicated at 11, providing an inward projection which abuts the inner side of the flange 6 and holds the head against outward sliding on the tube, inward sliding of said head being prevented by the inwardly bent end 10 thereof which engages the washer 8. The inwardly stamped portion 11, which is preferably continuous throughout the circumference of the head 9, also provides an external groove in said head for engagement with a shuttle holder in an ordinary bobbin. Between this groove and

the inner end of the head, the latter is preferably stamped to provide it with a plurality of external circumferential shoulders 12 which prevent slippage of the thread thereon.

The construction illustrated in Fig. 5 may be considered as the same as that above described, with the exception that three external grooves 11^a are provided in the head 9, any one of which or all of which may engage a shuttle holder within a bobbin. For a similar purpose, two circumferential grooves 11^a and a plurality of longitudinal grooves 13 are shown in Fig. 6, said grooves intersecting each other. The grooves 13 are shown at one side of the bobbin but it is to be understood that the entire circumference of the bobbin is provided with such grooves.

In Fig. 7, the bobbin head 9 is shown of greater length than in the other views, and it is provided with a pair of circumferential grooves 11^b and with longitudinal grooves 13^a throughout its circumference for engagement with suitable bobbin holding means in the shuttle, which means form no part of the present invention.

A bobbin constructed in or substantially in accordance with the present disclosure is easy to manufacture, inexpensive, exceptionally light and durable, is comparatively small in diameter and hence permits the carrying of a large amount of thread, and is unaffected by moisture, whereas the usual dye liquors and steam often used in treating the thread or yarn, will materially swell or expand the ordinary wooden bobbins.

Excellent results may be obtained from the details disclosed and they may therefore well be followed, but within the scope of the invention as claimed, numerous modifications may be made and obviously any adequate materials may be used in constructing the device. I have found the most practical material to be sheet aluminum, as it is light and durable, may be easily stamped into shape, and is not subject to corrosion or rusting.

I claim:

1. A bobbin comprising an elongated tube having a transverse flange at one end, a driving washer contacting with the outer side of said flange, and a hollow head secured around one end portion of the tube and surrounding said washer, said head having a portion engaging the outer side of the washer to secure the latter against the aforesaid flange.

2. A bobbin comprising an elongated tube

having a transverse flange at one end, a driving washer contacting with the outer side of said flange, and a hollow head secured around one end portion of said tube and said washer, said head having an inwardly directed portion abutting the aforesaid flange to hold the head against outward movement along the tube, said head also having a second inwardly extending portion engaging the outer side of said washer to secure the latter in place and to hold the head against movement along the tube in the other direction.

3. A bobbin comprising an elongated tube having a lateral outstanding circumferential projection at one end, a hollow head secured around one end portion of said tube and surrounding said projection, said head having an inwardly stamped portion around its circumference forming an inward projection abutting the inner side of said first named projection, said inwardly stamped portion also providing an external groove in the head for engagement with the bobbin holder of a shuttle, and a driving washer within the outer end of said head secured against the outer side of said first named projection.

4. A bobbin comprising an elongated tube having a lateral outstanding flange at one end, a hollow head secured around one end portion of said tube and surrounding said flange, said head having an inwardly stamped portion around its circumference forming an inward projection abutting the inner side of said flange and an external groove for engagement with a bobbin holder of a shuttle, and a driving washer within the outer end of said head abutting the outer side of said flange, said outer end of the head being inwardly bent against the outer side of said washer.

5. A sheet metal bobbin having an enlarged head at one end, said head having inwardly stamped portions providing external circumferential grooves in spaced relation and external longitudinal grooves whose ends open into said circumferential grooves.

6. A structure as specified in claim 5, said head having additional inwardly stamped portions providing longitudinal grooves from the outer end of said head to the first circumferential groove, the two sets of longitudinal grooves being in alignment with each other.

In testimony whereof I have hereunto affixed my signature.

LOUIS ALEXANDRE CADORET.
